UNITED STATES PATENT OFFICE

BENJAMIN G. CAMPBELL, OF OAKLAND, CALIFORNIA, ASSIGNOR OF ONE-HALF TO C. C. WING, OF OAKLAND, CALIFORNIA

MILK-CAP-SECURING MEANS

Application filed April 18, 1927. Serial No. 184,590.

This invention relates to the retaining of protecting means or caps over the mouths of bottles and the like. It has been found desirable to place over the mouths of milk and similar bottles, to protect the pouring edge thereof, a suitable cap covering retained in position by holding means, which latter is removed by the housewife when it is desired to lift the cap or cover from the bottle mouth and pour the contents from the bottle. The holding means now employed are objectionable, as in most instances they require a tool or prying implement to release the same and often remain on the neck of the bottle when it is washed by the housewife and returned to the distributor for refilling. The failure to completely remove the holding means from the bottle necessitates the dairy, distributor, or filling station, as the case may be, maintaining an attendant or operator for this purpose, and entails considerable expense both in labor and in loss of time.

The present invention has for its principal object to provide a form of cap holding means, which, when in position, will securely hold the cap in position over the bottle mouth, and which is capable of ready removal by the housewife without the necessity of tools or implements, and when released from the bottle cap, is also severed from the bottle. Another object is to provide a means of the above type which is adaptable for ready disposal by the housewife, is extremely inexpensive in its application and use, and is also efficient for the purpose intended.

To those skilled in the art of bottle capping, particularly of milk-bottle type having a skirted cap, it is well known that the capping is done by machinery, the bottles filled with milk passing through the filling and capping machine at a very rapid rate of speed. For this reason it is not possible to give detailed individual treatment to each bottle, and therefore the sealing means must be simple, quickly applied and be certain of holding. For this reason the plurality of wrappings accomplishes a new result in a new way, in that the stress or tension exerted on the cord ends is absorbed in the plurality of wrappings and not upon the sealing me-

dium, the result of such structure being that the sealing medium has practically no stress thereupon during the period it is drying, coagulating, or otherwise adhering to the cord to securely position the cord ends. This, therefore, permits passage of bottles through the capping machine at a very high rate of speed with practically no inspection and insures a very simple, efficient and inexpensive means to securely hold or maintain the skirted cap over the bottle.

The invention consists broadly in wrapping or winding a cord, tape, paper, twine, wire or other flexible element, either elastic or nonelastic, a plurality of times about the skirt of a bottle cap to hold the same in position on the bottle mouth, crossing or lapping the ends of the element and securing the wrappings together at their point of crossing or at one or more points within their length by the application thereto of sealing wax, or other material capable of easy application and preferably fragile when set; to prevent the releasing of the wrappings, and with the ends of the material lying free and of a length to afford a grip being had thereon whereby the securing means may be readily fractured, or broken, or torn, releasing the flexible element on one of the ends thereof being grasped and manipulated to fracture or disrupt the securing or sealing means.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

Referring to the drawings forming part of the present application:—

Fig. 1 is a view in elevation of the preferred embodiment of my invention as applied to the skirt of a sealing cap for the conventional type of milk bottle.

Fig. 2 is an enlarged detail view of a por-

tion of the element at the point of overlap of its ends.

Fig. 3 is a view similar to Fig. 2 with the sealing means applied.

Referring to the drawings wherein like characters of reference designate corresponding parts, 1 indicates the neck of a conventional milk bottle, over the mouth and the upper pouring edge of which is positioned a sealing cap of any of the conventional types, having a skirt 3 preferably pleated at 3' enabling the same to be tightly drawn into contact with the outer surface of the bottle neck 4.

15 A flexible member 5 is wrapped or wound under tension a plurality of times around the skirt 3, and at one or more places the wrappings where they extend beyond each other, are secured together by the application of 20 sealing wax, shellac, or other substance or element 6. I prefer a substance which is readily fracturable when the same hardens or sets on the application thereto of a pressure less than the breaking strain of the flexible member, 25 and while a plastic element is shown and described, it is understood that a disk or sheet of flexible material may equally as well be employed. The preferred point of application of the substance or element 6, as illustrated in the drawing, is where the terminal portions of the flexible member cross or overlap, permitting the end 7 of the member 5 to project free of the sealing member or element 6 and afford extensions which may be manipulated to break the seal or element 6 when it is desired to release the flexible element from its position around the cap skirt.

With the cap in position as in the drawings, and the member 5 retaining the same in position, against the bottle neck 4, the sealing means thus preventing the unwinding or unwrapping of the member 5, the housewife or operator to release the cap grasps one of the ends 7 of the member 5, either end being 40 available for this purpose, and manipulates the same by pulling it outwardly away from the skirt or toward the sealing means or element 6 with sufficient force to fracture or tear the sealing means permitting the releasing 45 or unwinding of the member 5 from the cap skirt leaving the cap free for ready removal from the bottle mouth. Then when the member 5 is released from the skirt, it is free of the bottle neck and cap and may be disposed of as desired. It is to be understood that the overlapping portions of the member 5 are not tied together but are only held from releasing 50 by the securing or sealing element 6.

By wrapping the member 5 a number of 55 times around the skirt 3, it has been discovered that a thinner, weaker or more readily fracturable sealing means, or less of a sealing means of great strength, may be employed than when a single wrapping of the member 60 is applied. This is possible due to the fact as

illustrated in the drawings that the sealing means engages each wrapping and unites one to the other. The multiple wrapping of the member 5 about the skirt also reduces the period required for holding the member 5 under tension until the sealing means hardens, thickens, dries or congeals sufficiently to tightly retain the wrapping member in place.

I claim:—

75 A bottle closure having a depending skirt portion adapted to enclose the mouth of a bottle, a continuous flexible cord wrapped a plurality of times around said skirt portion and having its ends releasably positioned and a sticky sealing medium applied in a substantially sticky state to the releasably positioned end portions of said cord.

80 In testimony whereof I have signed my name to this specification.

85 BENJAMIN G. CAMPBELL.
